AUTOMATIC TELEPHONE SYSTEM

Harry G. Evers, Chicago, Ill., assignor to Associated Electric Laboratories, Inc., Chicago, Ill., a corporation of Delaware

Application January 29, 1934, Serial No. 708,783

20 Claims. (Cl. 179—17)

This invention relates in general to automatic telephone systems, but more in particular to small systems suited for installation in towns or villages. An automatic telephone system of this type is generally known as a Community Automatic Exchange or C. A. X., and may have a capacity of about twenty lines, more or less. Usually the lines are party lines having either bridged or grounded ringing circuits over which such subscribers are signaled by means of code ringing. Provision is also made for trunking calls to and from distant exchanges.

The object of the present invention is to provide a novel and improved all-relay community automatic exchange of the foregoing character.

One of the features of the invention relates to the all-relay finder-connector links for interconnecting the various lines in this system.

Another feature of the invention relates to the manner in which both the trunk lines and subscribers' lines are connected to a finder-connector link especially the line and trunk hunting operations of the finder and connector units relays.

Another feature of the invention relates to an improved pulsing arrangement for repeating the pulses received from a calling line.

Another feature of the invention relates to circuit arrangements whereby the finder-connector link switches straight through cutting off the local talking bridges on outgoing trunk calls.

Another feature of the invention relates to the circuit arrangements for selecting and connecting various code rings to called subscribers' lines.

These and other features of the invention will be apparent from the following detailed description of the invention.

Referring now to the drawings, comprising Figs. 1 to 4, inclusive, there is shown by means of the usual circuit diagrams one of the all-relay finder-connector-links, two different line circuits and two substation circuits by means of which the invention may be described and understood.

Fig. 1 shows a group of finder group relays FGR for connecting the line conductors and test conductors of the various groups of lines and trunk lines to one of the finder-connector all-relay links. The groups of lines are divided into four groups of five lines each and are designated as the 10, 20, 30, and 40 groups. Relays such as relays 10-40, inclusive, are for connecting the test and line conductors of their respective groups to the link circuit. In the upper left-hand corner of Fig. 1 is shown the line circuit #15 of a line in the 10-group. A plurality of substations such as S are connected to this line. As will be seen, the line

conductors of this line, or line 15, are multiplied and terminate in armatures 11 and 12 in the calling or finder end of the links, while the calling test conductor of this line is likewise multiplied and terminates in armatures 13 in the various links. The line conductors and the called test conductor extend by way of a three-conductor cable 4 to the outgoing ends of the links wherein these conductors terminate in armatures on the connector group relays, such as relay 210. The last three line connections in the 40-group are connected to trunk lines extending to a distant exchange and terminate in the links similar to the local lines. The trunk line conductors are also connected to the outgoing end of the links in a manner similar to that described for line 15. Each group of lines has a common start conductor, such as conductors 5 and 5', which extends, as shown, to the finder group relays in each link, and also through resistances to a common start conductor 99 which is connected in series through all of the links. The group of finder units relays FUR shown to the right are for connecting the line of any selected group to the control circuits in the link.

Fig. 2 shows a group of connector unit relays CUR for connecting the link to a particular called line in any called group as determined by the operated connector group relay. The group of connector group relays CGR are for connecting the outgoing end of the link to any line in any group. In the right-hand end of Fig. 2 is shown the line circuit of the grounded line 25 and a plurality of substations thereon. This line circuit is similar to the line circuit shown in Fig. 1 and has been altered for use on a grounded line as indicated by the circuit changes and small circles.

Line 25 is a grounded line and is connected to the incoming end of the link by the three-conductor cable extending to armatures 21, 22 and 23, in Fig. 1. All of the trunk lines and all of the subscribers' lines in all of the groups terminate in the outgoing end of the link in the manner illustrated by line 25. In addition each line has an extra test conductor, such as conductor 234. This extra test conductor is only connected by a jumper, such as jumper 249, to the regular test conductor of all trunk lines in a group but the last trunk line.

Fig. 3 shows a group of relays in the control circuit of one of the links and also shows a group of code selecting relays by means of which the desired ringing code is selected.

Fig. 4 shows another group of relays in the control circuit of the same link.

Briefly the operation of the system is as follows:

- 5 When a calling subscriber initiates a call the test conductor of the calling line is marked with calling potential and the calling group is marked in all the finder-group relays in all the links. The start conductor is grounded and the finder
- 10 group relays in the first idle link operate in sequence to find the calling group. When the calling group is found the last operated finder group relay connects all of the conductors of all of the lines in the calling group to the finder units relays which now operate in sequence until the marked calling line is found.
- 15

When the calling line is found the transfer relay in the link is operated to prepare another idle link for use and the calling line is connected

- 20 to the control circuits of the link in use. The first digit transmitted by the calling subscriber operates impulse repeating relays to successively operate the corresponding connector group relays. Only the last operated connector group
- 25

relay is maintained energized to connect the conductors of the called group to the connector units relays of the link. The second digit reoperates the impulse repeating relays to successively operate the corresponding connector unit relays.

- 30 Only the last operated connector unit relay is maintained energized to connect the conductors of the called line to the link control circuits. The third digit reoperates the impulse repeating relays to select the ringing code. If the called line is
- 35

idle the ringing interrupter (not shown) transmits ringing current over the selected code ringing conductor to ring the code of the called line. In outgoing trunk calls the calling line is found in the same manner as just described and in re-

- 40 sponse to dialling the two digits designating a trunk call the corresponding connector group and unit relays operate as before to connect with the first trunk in the group. In case the first trunk in this group is busy then the remaining connector unit relays are successively operated to hunt
- 45

for an idle trunk in this group. When an idle trunk line is found the link switches through cutting off the local talking bridges.

Local call

- 50 It will now be assumed that subscriber S desires to call subscriber S'. When the subscriber S removes his receiver a circuit is completed for energizing line relay 8 over the following circuit: from ground by way of armature 78 and resting contact, through the winding of relay 8, over the lower talking conductor 1 of line 15 through the subscriber's substation loop over the upper heavy talking conductor 2, armature 11, and through the upper winding of relay 8 to battery. Relay 8 at armature 86 disconnects the called test conductor 3 from the cut-off relay 7 at its resting contact and at its working contact grounds conductor 3 which extends by way of the three conductor cable 4 to busy the calling line at its called terminals, at armature 87 connects the cut-off relay 7 to armature 13 by way of armature 66 to mark line 15 as a calling line in the finder group relays. At armature 88 relay 8 grounds start conductor 5 by way of armature 67 and resting contact, thereby marking the calling group in the finder group relays FGR in all the links. Responsive to relay 8 grounding start conductor 5 a circuit may be traced for energizing the combined start and line relay in the first idle link in the chain as
- 55
- 60
- 65
- 70
- 75

follows: from grounded armature 88, armature 67 and resting contact, conductor 5, resistance R1, conductor 99, armature 103 and resting contact, and through the winding of combined start and line relay 160 to battery.

Relay 160, upon energizing over the above-traced circuit, at armature 161 and its working contact completes the circuit for energizing slow-to-release relay 180 from grounded armature 132. At armature 181 relay 180 prepares a point in the circuit for marginal switch-through relay 130, at armature 182 completes an obvious circuit for energizing slow to release relay 190, and at armature 183 and working contact connects ground to the lower winding of the transfer line test relay 100. At armature 191 relay 190, upon energizing, prepares a point in the impulsing circuit, at armature 192 grounds conductor 124 to complete an energizing circuit for relay 360, at armature 193 grounds the connector lock conductor 126 to provide a locking circuit for the connector group and unit relays when the same are operated, at armature 194 and resting contact, disconnects one of the ground connections from the common all link busy conductor ALB, and at its working contact grounds conductor 14 to provide a locking circuit for the finder group unit relays, the code selecting relays, and other relays in the link circuit. The circuit for energizing relay 360 may be traced as follows: from grounded conductor 124 by way of armature 315 and resting contact, and through the winding of relay 360 to battery.

At armature 361 relay 360 disconnects the first code selecting relay C1 at its resting contact and prepares a circuit for the first connector group relay 210 at its working contact, at armature 362 opens the circuit to locking conductor 146 at its resting contact and at its working contact connects up conductor 217. At armature 363 relay 360 at its resting contact opens the even pulse conductor 147 extending to the code selecting relays, and at its working contact connects up the even pulse conductor extending to the connector group relays, at armature 364 and resting contact opens the circuit extending to the odd pulse conductor 148 extending to the code selecting relays and at its working contact connects up the odd pulsing conductor to the connector group relays. At armature 365 relay 360 connects dial tone by way of the dial tone condenser and armature 314 to the upper talking conductor 108, at armature 366 prepares a point in its own locking circuit and at armature 367 prepares a circuit for energizing relay 350 in series with relay 360.

When ground is connected to the lock conductor 14 a circuit may be traced for energizing the first finder group relay 10 as follows: from grounded conductor 14, armature 104 and resting contact, armature 112 and resting contact, group start conductor 96, armature 48, armature 38, armature 28, armature 18, and through the winding of slow to operate relay 10 to battery. Relay 10, upon energizing, closes a locking circuit for itself at armature 16 before operating the remaining armatures. This locking circuit may be traced from grounded lock conductor 14 by way of armatures 45, 35, 25, and armature 16. Relay 10, upon fully operating, closes its armatures 11, 12, 13, etc., to connect all of the lines including lines 11, 12, 13, 14 and 15 in the 10-70 group to this link circuit, at armature 17 completes the circuit for energizing slow to operate relay 20, at armature 18 opens a point in its original energizing circuit only after the above traced locking circuit has been completed, and at 75

armature 19 connects the group marking ground extending by way of conductors 5 and 56 to conductor 98.

Since relay 20 is a slow to operate relay, the 5 group test relay 110 will operate and open the circuit for energizing relay 20 before the latter can operate in case relay 10 at armature 19 connects ground to conductor 98. However, in order to explain the hunting operations of the finder 10 group relays FGR it will be assumed for the time being that relay 10 does not connect ground to conductor 98, and therefore relay 110 will not operate and open the circuit to relay 20 before it 15 can fully energize. In this case relay 20 operates its armature 26 after an interval, to first complete 20 its locking circuit by way of armatures 26, 35, and 45 to grounded lock conductor 14. At its upper 25 armatures such as armatures 21, 22, 23, etc., relay 20 connects all the lines in the 20-group to the link circuit. At armature 25 relay 20 opens the locking circuit of relay 10 to cause the latter relay to deenergize and open the circuits to the lines in the 10-group. At armature 27 relay 20 completes the circuit for slow to operate relay 30, at armature 28 opens a point in its original energizing 30 circuit, and at armature 29 connects the common group start conductor 5' by way of conductor 57 to the group test conductor 98. In case the start conductor 5' is grounded then the test relay 110 35 is energized to open the circuit to relay 30 before slow to operate relay 30 has had sufficient time to operate its armatures. In the same manner as just described slow to operate relays 30 and 40 operate to connect the lines of the 30 and 40 line 40 groups to the link and to connect the start conductor of such groups to the group test conductor 98. When the finder group relay corresponding to the calling group is fully energized, a circuit may be traced for energizing the group test 45 relay 110 from grounded start conductor, such as conductor 5, conductor 56, armature 19, group test conductor 98, armature 102, and through the upper winding of group test relay 110 to battery.

Group test relay 110 operates very quickly to 45 open the circuit at armature 112 and resting contact extending to the finder group relays so as to open the circuit completed for the succeeding finder group relay before this relay has had sufficient time to energize. At armature 111 relay 110 connects ground through resistance 107 to 50 the winding of relay 160 to maintain relay 160 in energized position and also for reducing the click in the calling subscriber's receiver when the calling line is connected to the link, at armature 113 55 short circuits its lower winding to make this relay slow to release, and at armature 112 and working contact connects the grounded lock conductor 14 to the line start conductor 97 by way of resting contact and armature 104.

When line start conductor 97 is grounded by the 60 operation of group test relay 110, finder unit relay 50 is energized over the following circuit: from grounded conductor 97 by way of armatures 95, 85, 75, 65 and 55, and through the winding of 65 slow to operate relay 50 to battery. At armature 54 relay 50 completes a locking circuit for itself from grounded lock conductor 14 by way of the normally closed springs controlled by armatures 94, 84, 74, and 64. At armature 55 and resting 70 contact relay 50 opens a point in its original energizing circuit only after its locking circuit has been completed and at its working contact completes the circuit for slow to operate relay 60. At 75 its upper armatures relay 50 connects the line and test conductors of line 11 to the line and test con-

ductors of the link. In case relay 20 instead of relay 10 were operated, then the upper armatures of relay 50 would connect the line and test conductors of line 21 to the link. Since line 11 is not calling, then negative battery through the winding of the cut-off relay is not connected to the test lead of line 11 with the result that no circuit is completed for the transfer line test relay 100. Since relay 100 does not operate slow to operate relay 60 has had sufficient time to energize 10 and operate its armatures. The circuit for energizing relay 60 extends by way of grounded conductor 97, armatures 95, 85, 75, and 65, and their resting contacts, and by way of armature 55 and its working contact through the winding of relay 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 - upper winding from grounded lock conductor 14, at armature 102 opens the circuit of group test relay 110 to cause this relay to deenergize. At armature 103 and resting contact relay 100 opens 5 the original energizing circuit of line relay 160 and at working contact of armature 103 transfers the start lead 99 to the next finder-connector link by way of conductor 99'. At armature 105 relay 100 short circuits its lower winding 10 to connect direct ground to conductor 79 to mark the calling line busy at the calling end by grounding conductor 9 and also to ground conductor 3 by way of armatures 16 and 86 to busy this line at the called end. At armatures 101 and 15 106 relay 100 completes a new circuit including the calling subscriber's loop for maintaining line relay 160 in operated position. This circuit may be traced as follows: from ground by way of armature 172 and resting contact, armatures 144 20 and 136, normally closed springs controlled by armature 122, armature 106, conductor 69, armature 91, armature 11, conductor 1 through the calling substation loop to conductor 2, armatures 12 and 92, conductor 89, armature 101, normally 25 closed springs controlled by armature 121, armature 131 and resting contact, armature 141, through the upper left-hand winding of repeating coil RC, and through the winding of line relay 160 to battery.
- 30 Dial tone is now transmitted to the calling line in the following manner. When dial tone is connected to talking conductor 108, as previously described, the tone induced in the upper right-hand winding of repeating coil RC is induced 35 into the upper left-hand winding of repeating coil RC and thence over the previously traced circuit through the calling substation loop in the well known manner.
- When subscriber S hears the dial tone such 40 subscriber will dial the first two digits of the called number in accordance with the line number of the desired subscriber, and then the third digit in accordance with the ringing code assigned to the desired subscriber on this line. In 45 response to the operation of the calling device at substation S for the first digit, the circuit extending over the heavy talking conductor to relay 160 is interrupted in accordance with the digit dialled. Whenever the dialling circuit is interrupted line relay 160 deenergizes and at armature 161 and working contact temporarily opens the circuit to slow to release relay 180, which, however, is maintained energized during the impulsive period due to its slow release characteristics, and at its resting contact grounds the 50 impulsive conductor 118 by way of armature 191 and grounded armature 132. Each time the impulsive conductor 118 is grounded a circuit is completed for slow to release series relay 310 55 as follows: from grounded impulse conductor 118, armature 302, armature 332 and resting contact, and through the winding of slow to release relay 310 to battery. At armature 311 relay 310 completes an obvious circuit for energizing relay 60 320, and at armature 312 opens a point in the circuit extending to the extra test conductor 319. Due to its slow release characteristics relay 310 is maintained energized during the impulsive period, and therefore maintains relay 320 likewise 65 energized. At armature 321 relay 320 opens a point in the testing circuit, at armature 322 prepares a point in the circuit extending to the two-step marginal busy relay 330, at armature 323 completes a locking circuit for relay 360 from 70 grounded lock conductor 14 by way of armature 355 and resting contact, and at armature 324 completes an energizing circuit for slow to operate relay 313 from grounded lock conductor 14 through the normally closed springs controlled by armature 315. At armature 314 relay 313 opens the dial tone circuit, at armature 315 and its resting contact opens the original energizing circuit for relay 360, which is now maintained energized over its locking circuit, and at the working contact of armature 315 completes an obvious 10 locking circuit for itself from grounded conductor 124, as well as opening its original energizing circuit at the normally closed springs controlled by armature 315.
- The first time impulse conductor 118 is grounded differential relay 380 is energized over the following circuit: from ground on the impulse conductor 118, armature 302, armature 332 and resting contact, armature 393 and resting contact, and through the lower winding of relay 380 to 15 battery. At armature 381 relay 380 connects conductor 373 to conductor 217 for energizing the first connector group relay 210, as follows: from grounded lock conductor 126, armatures 247, 237 and 227, conductor 217, working contact and 20 armature 362, resting contact and armature 352, armature 381, armature 351 and resting contact, armature 361 and working contact, conductor 373, and through the winding of relay 210 to battery. At armature 382, relay 380 grounds the odd pulse 25 conductor 377 without effect at this time because armature 229 is not operated, at armature 383 prepares a circuit for the upper winding of differential relay 380, at armature 384 and its working contact completes a circuit for maintaining 30 differential relay 380 energized and for short-circuiting the lower winding of relay 390 as follows: from ground on the impulse conductor 118, armature 302, armature 332 and resting contact, armature 393 and resting contact, through the 35 lower winding of relay 390, working contact and armature 384, armature 324 to grounded lock conductor 14. At the end of the first impulse when line relay 160 again energizes, ground is removed from impulse conductor 118 with the result that 40 the short circuit around the lower winding of relay 390 is removed and relay 390 now energizes in series with the lower winding of differential relay 380 from grounded lock conductor 14, armature 324 and armature 384 and working contact, through the lower winding of relay 390 and the lower winding of differential relay 380 to battery. At armature 391 relay 390 prepares the circuit for grounding the even pulse lead 375, at armature 392 prepares a point in the ringing circuit, 45 at armature 393 and resting contact opens a point in the original energizing circuit through the lower winding of differential relay 380 and at its working contact prepares a circuit for the upper winding of relay 390, and at armature 395 completes a circuit for energizing relay 370 as follows: from grounded lock conductor 14, armature 324, armature 385 and through the winding of relay 370 to battery. At armature 371 relay 370 closes a shunt around armature 391, and at armature 372 50 prepares a locking circuit for itself by way of resting contact of armature 384 independent of armature 395. In response to the second impulse conductor 118 is again grounded, and at this time a circuit may be traced for maintaining relay 390 55 energized through its upper winding and for de-energizing the differential relay 380 as follows: from ground over the impulsive circuit as previously described to armature 393, and from thence by way of its working contact, resting contact 60 70 75

and armature 303 through the upper winding of relay 390 to battery for maintaining relay 390 energized, and by way of armature 383 through the upper winding of differential relay 380 to battery to cause the differential relay to deenergize. Since both the windings of differential relay 380 are energized at this time and since these windings are equal and oppose each other, relay 380 therefore deenergizes.

When connector group 210 energized over the previously traced circuit, said relay at its upper armatures connected all of the lines in the 10-group to the link, at armature 218 completes a locking circuit for itself through armatures 227, 237, 247 and grounded connector lock conductor 126, and at armature 219 prepares the circuit for relay 220.

Differential relay 389, upon deenergizing, at armature 381 opens the original energizing circuit of relay 218, which is now maintained energized over its locking circuit, at armatures 383 and 384 simultaneously opens the circuits through its upper and lower windings, respectively, while at the resting contact of relay 384 completes the previously traced locking circuit for relay 370. At armature 382 relay 380 disconnects ground from the odd pulse conductor 377 at its working contact and at its resting contact connects ground to the even pulse conductor 375 for energizing the second connector group relay 220 as follows: from ground by way of armature 304 and resting contact, armature 382 and resting contact, through armatures 391 and 371 in multiple, armature 353 and resting contact, armature 363 and working contact, conductor 375, armature 219 and through the winding of relay 220 to battery.

At its upper armatures relay 220 connects the line and test conductors of the 20-group to the link, at armature 227 opens the locking circuit of relay 210 which deenergizes, at armature 228 completes its own locking circuit from grounded lock conductor 126 and at armature 229 connects the odd pulse conductor 377 to the winding of relay 230.

When line relay 160 energizes at the end of the second impulse ground is removed from conductor 118, thereby opening the circuit extending to the upper winding of relay 390, whereupon the latter relay deenergizes. The impulse repeating relays 380 and 390 are now the same as at the start of the impulsive period and in case more than two impulses are transmitted for the first digit relay 380 is again energized at the start of the third impulse in the same manner as previously described for the first impulse. At armature 384 and resting contact the locking circuit to relay 370 is opened with the result that the latter relay now deenergizes and in response to the operation of armature 382 ground is connected to the odd pulse conductor 377 for energizing connector group relay 230 as follows: from ground by way of armature 384 and resting contact, armature 382 and its working contact, armature 364 and working contact, odd pulse conductor 377, armature 229 and through the winding of relay 230 to battery. At its upper armatures relay 230 connects the line and test conductors of all the lines in the 30-group to the link, at armature 237 opens the locking circuit of relay 220 which thereupon deenergizes, at armature 238 completes its own locking circuit from grounded connector lock conductor 126, and at armature 239 connects the even pulse conductor 375 to relay 240.

When line relay 160 reenergizes at the end of

the third impulse, relays 390 and 370 reenergize in the same manner as previously described. When line relay 160 deenergizes at the start of the fourth impulse the circuit through the upper winding of differential relay 380 is again completed with the result that the differential relay 380 now deenergizes to transmit an impulse over the even pulse conductor 375 to complete an energizing circuit for connector group relay 240. This circuit may be traced from ground at the resting springs of armature 304, armature 382 and resting contact, and from thence over the previously traced circuit to the even pulse conductor 375, through armature 239 and the winding of relay 240 to battery. At armature 241 relay 240 opens the locking circuit of connector group relay 230 which causes this relay to deenergize. At its upper armatures relay 240 connects the line and trunk conductors in the 40-group to the link, at armature 246 prepares a point in the trunk switch-through circuit, and at armature 243 completes a locking circuit for itself from grounded lock conductor 126. Connector group relay 230, upon deenergizing, disconnects the lines of the 30-group from the link. At the end of the fourth impulse, when line relay 160 reenergizes, the circuit through the upper winding of relay 390 is opened in the same manner as previously described with the result that this relay now deenergizes.

In this case, since subscriber S is calling subscriber S', only two impulses have been transmitted with the result that connector group relay 220 is energized as previously described to connect the lines in the 20-group to the link. After the first series of impulses slow to release relay 310 deenergizes after an interval and at armature 311 opens the circuit of relay 320. At armature 324 relay 320 opens the circuit of relays 380 and 390 if either one or both should be energized at this time, and at the normally closed springs controlled by armature 323 completes a circuit for energizing relay 350 in series with relay 360, as follows: From grounded lock conductor 14, normally closed springs controlled by armature 323, 45 armature 367, through the upper winding of relay 350, and through the winding of relay 360 to battery. Relay 360 is maintained energized over this circuit while relay 350 at armature 355 prepares a locking circuit for itself. At armatures 351 to 354, inclusive, relay 350 connects up the control conductors extending to the connector unit relays.

Subscriber S now dials the unit digit or digit 5 of the called line. In response thereto line relay 160 again deenergizes five times. In response to the first impulse slow to release relay 310 again energizes over the circuit previously traced, and the impulse repeating relay 380 likewise again energizes. At armature 311 relay 310 again completes the circuit for energizing relay 320 and the latter relay at armature 323 completes a locking circuit from grounded lock conductor 14 through the lower winding of relay 350 to hold this relay in energized position while at the normally closed springs controlled by armature 323 the circuit through the upper winding of relay 350 and the winding of 360 is opened to cause the latter relay to deenergize. At armature 324 relay 320 again connects grounded lock conductor 14 to armature 384. At armatures 361 to 364, inclusive, relay 360 disconnects the control conductors from the connector group relays and prepares a circuit for connecting the control conductors to the code selecting relays CRS in Fig. 3, and at armature 75

- 365 disconnects dial tone. At armature 381 relay 380 completes a circuit for energizing the first connector unit relay 250 as follows: from grounded connector lock conductor 126 by way of armatures 296, 286, and 266, conductor 256, working contact and armature 352, armature 381, armature 351 and working contact, conductor 374, and through the winding of relay 250 to battery.
- 10 At armature 257 relay 250 completes a locking circuit for itself from the grounded connector lock conductor 126, and at armatures 258 and 259 prepares a circuit for the second connector unit relay 260. At its upper armatures relay 250 connects the line and test conductors of line 21 to the link. When line relay 160 energizes at the end of the first impulse, relays 390 and 370 energize from ground on the lock conductor 14 in the same manner as previously described. When line relay 160 deenergizes in response to the second pulse, differential relay 380 deenergizes while relay 390 is maintained as previously described. At armature 382 relay 380 completes a circuit for energizing the second connector unit relay 260 as follows: from ground by way of armature 304 and resting contact, armature 382 and resting contact, armatures 371 and 391 in multiple, armature 353 and working contact, conductor 376, armature 259, and through the winding of relay 260 to battery. At armature 267 relay 260 completes a locking circuit for itself from the grounded connector lock conductor 126, at armature 266 opens the locking circuit of relay 250 to cause its deenergization and at armatures 268 and 269 prepares the circuit for the next connector unit relay 270. At its upper armatures relay 260 connects the line and test conductors of line 22 to the link. Relay 250, upon deenergizing, at its upper armature disconnects the line and test conductors of line 21 from the link. At the end of the second impulse when line relay 160 reenergizes the circuit through the upper winding of relay 390 is opened with the result that this relay now deenergizes.
- 45 When line relay 160 deenergizes in response to the third impulse, differential relay 380 is again energized as previously described. At armature 382 relay 380 completes a circuit for energizing relay 270 as follows: from ground by way of armature 304 and resting contact, armature 382 and working contact, armature 354 and working contact, over the odd pulse conductor 378, through armature 269 and the winding of relay 270 to battery. At armature 277 relay 270 completes a locking circuit for itself from the grounded connector lock conductor 126, at armature 276 opens the locking circuit of relay 260 which thereupon deenergizes, at armatures 278 and 279 prepares the circuits for energizing relay 280, and at armature 275 prepares a point in the switch-through circuit. At its upper armatures relay 270 connects the line and test conductors of line 23 to the link. Relay 260, upon deenergizing at its upper armatures disconnects line and test conductors of line 22 from the link. At the end of the third impulse when line relay 160 reenergizes, relays 390 and 370 are again energized over the circuit previously traced.
- 70 When line relay 160 deenergizes in response to the fourth impulse the circuit through the upper windings of relays 380 and 390 is again completed to cause the deenergization of differential relay 380 and to maintain relay 390 in operated position. At armature 382 relay 380, upon deenergizing, completes the circuit for energizing relay 280 as follows: from ground by way of armature 304 and resting contact, armature 382 and resting contact, armatures 371 and 391 in multiple, armature 353 and working contact, over the even pulse conductor 376 through armature 279 and the winding of relay 280 to battery. At armature 287 relay 280 completes a locking circuit for itself from grounded lock conductor 126, at armature 286 opens the locking circuit of relay 270 which thereupon deenergizes, at armatures 288 and 289 prepares the circuits for energizing relay 290 and at armature 285 prepares another point in the switch-through circuit. At its upper armatures relay 280 connects the line and test conductors of line 24 to the link. Relay 270, upon deenergizing, at its upper armatures disconnects the line and test conductors of line 23 from the link. When line relay 160 reenergizes at the end of the fourth impulse the circuit through the upper winding of relay 390 is opened, thereby causing the deenergization of this relay.
- 15 When relay 160 deenergizes in response to the fifth impulse, relay 380 again energizes to complete a circuit for energizing relay 290 as follows: from grounded armature 304 over the previously traced circuit to the odd pulse conductor 378 and thence by way of armature 289 and the winding of relay 290 to battery. At armature 384 relay 380 causes the deenergization of relay 310 as previously described. At armature 297 relay 290 completes a locking circuit for itself from grounded lock conductor 126, at armature 296 opens the locking circuit of relay 280 to cause its deenergization, and at armature 295 prepares another point in the switch-through circuit. At its upper armatures 291, 292, 293, and 294 relay 290 connects the line and test conductors of line 25 to the link. Relay 280, upon deenergizing, at its upper armatures disconnects the line and test conductors of line 24 from the link. When line relay 160 reenergizes at the end of the fifth impulse relays 390 and 370 again energize as previously described.
- 30 After the impulsing period slow to release relay 310 and then relay 320 deenergize. At armature 324 relay 320 opens the circuit of relays 380 and 390 to cause the deenergization of these relays, and at armature 323 opens the locking circuit extending to the lower winding of relay 350 to cause the latter relay to deenergize. At armatures 351 to 354, inclusive, relay 350 prepares the circuits extending to the code selecting relays CSR.
- 40 Subscriber S now dials the last or ringing digit assigned to the desired subscriber on line 25. In response to the first impulse line relay 160 again deenergizes and again closes the circuit for energizing slow to release relay 310 and differential relay 380. At armature 311 relay 310 again completes the circuit for energizing relay 320. At armature 321 relay 320 opens a point in the test circuit and at armature 322 connects the busy two-step marginal relay 330 to test conductor 125. Relay 380, upon energizing, at armature 381 completes a circuit for energizing the first code selecting relay C1 as follows: from grounded lock conductor 14 by way of armatures 154, 159, 167, 177 and 178, conductor 146, resting contact of armature 362 and said armature, resting contact and armature 352, armature 381, armature 351 and resting contact, armature 361 and resting contact, conductor 145 and through the winding of relay C1 to battery. At armature 196 relay C1 prepares a point for connecting the code ringing conductor 2-1 to conductor 139, at ar-

5 armature 197 prepares a circuit for connecting the code ringing conductor 1-1 to the called line, at armature 198 opens a point in the locking circuit of relay C3, at armature 199 completes a locking 5 circuit for itself from grounded lock conductor 14, at armature 148 prepares a point in the circuit for relay C2, and at armature 153 connects the test conductor of the called line to the winding of two step marginal busy relay 330 for testing 10 purposes.

10 Before describing the testing arrangement it is believed advisable to explain the operation of the code selecting relays in response to the code selecting digits dialled thereto. The impulse repeating relays 380, 390 and 370 operate in the same manner as previously described to transmit ground impulses from armature 304 to the even and odd conductors 147 and 148 to the code selecting relays. When relay 380 deenergizes in response to the second impulse of the code ringing digit a circuit is completed over the even pulse conductor 147 for energizing relay C2 as follows: from ground by way of armature 304 and resting contact, armature 382 and resting contact, armatures 391 and 371 in multiple, armature 353 and resting contact, armature 363 and resting contact, even pulse conductor 147, armature 149 and through the winding of relay C2 to battery. At armature 185 relay C2 prepares the code ringing conductor 2-3, at armature 188 connects up the code ring conductor 2-2, at armature 187 opens the locking circuit of relay C1 which thereupon deenergizes, at armature 188 completes a locking circuit for itself from grounded lock conductor 14, at armature 189 prepares a circuit for relay C3, and at armature 195 completes another point in the test circuit. Relay C1, upon deenergizing, at armature 198 prepares a locking circuit for relay C5, at armatures 196 and 197 disconnects the code ring conductors 2-1 and 1-1, at armature 149 opens the original energizing circuit of relay C2, and at armature 153 opens a point in the test circuit, which circuit, however, is maintained closed at armature 195.

45 In response to the third impulse, relay 380, upon energizing, completes the circuit for energizing the third code selecting relay C3 over the odd pulse conductor 148 as follows: from ground by way of armature 304 and resting contact, armature 382 and working contact, armature 354 and resting contact, armature 364 and resting contact, odd pulse conductor 148, armature 189 and through the winding of relay C3 to battery. At armatures 175 and 176 relay C3 prepares the circuit for the code ring conductors 3-1 and 3-3, at armature 177 opens the locking circuit of relay C2 which thereupon deenergizes, at armature 178 completes a locking circuit for itself from grounded lock conductor 14, at armature 179 prepares a circuit for relay C4, and at armature 184 maintains the test circuit closed. Relay C2, upon deenergizing, at armatures 185 and 186 disconnects the code ring conductors 2-3 and 2-2, and at armature 189 opens the original energizing circuit of relay C3.

55 Relay 380 deenergizes in response to the fourth impulse and again grounds the even pulse conductor 147 to complete a circuit by way of armature 179 for relay C4. At armatures 165 and 166 relay C4 connects the code ring conductor 3-2 and 1-2, at armature 167 opens the locking circuit of relay C3 which thereupon deenergizes, at armature 168 completes a locking circuit for itself from grounded lock conductor 14, at armature 169 prepares a circuit for relay C5, and at

5 armature 174 maintains the test circuit closed. Relay C3 deenergizes and opens the circuit to the selected code ring conductors. In response to the fifth impulse relay 380 again energizes to ground the odd pulse conductor 148 to complete an energizing circuit for relay C5 by way of armature 169. At armatures 157 and 158 relay C5 connects the code ring conductors 1-4 and 1-3, at armature 159 opens the locking circuit of relay C4 which thereupon deenergizes, at armature 162 completes a locking circuit for itself from grounded lock conductor 14 by way of armature 198, at armature 163 prepares the circuit for relay C6, and at armature 164 maintains the test circuit closed. Relay C4 deenergizes and disconnects the selected code ringing conductors and at armature 168 opens the original energizing circuit of relay C5.

10 Relay 380 deenergizes in response to the sixth impulse to ground the even pulse conductor 147 thereby completing an energizing circuit for relay C6 by way of armature 163. At armature 152 and its resting contact relay C6 prevents the connection of the lower group of code ring conductors including conductors 1-1, 2-2, 3-3, 25 1-2 and 1-3, to conductor 139, and at its working contacts prepares circuits for connecting the upper groups of code ringing conductors to conductor 139. At armature 155 relay C6 completes a locking circuit for itself from grounded conductor 14 and at armature 156 maintains the test circuit closed.

15 When relay 380 energizes in response to the seventh impulse said relay completes a circuit for energizing relay C1 over the following circuit: 35 from ground by way of armature 14, armature 154 and working contact, armatures 167, 177 and 181, conductor 146, resting contact and armature 362, resting contact and armature 352, armature 381, armature 351 and resting contact, armature 361 and resting contact, conductor 145, and through the winding of relay C1 to battery. Relay C1 again energizes and in this instance at armature 196 prepares a circuit for connecting up the code ring conductor 2-1. At armature 199 40 relay C1 completes a locking circuit for itself, at armature 149 prepares a circuit for relay C2 and at armature 198 opens the locking circuit of relay C5 which thereupon deenergizes.

20 Relay 380 deenergizes responsive to the eighth impulse to ground the even pulse conductor 147 to cause the reenergization of relay C2. At armature 185 relay C2 connects up the second code ring conductor 2-3, at armature 187 opens the locking circuit of relay C1, at armature 188 completes a locking circuit for itself from grounded lock conductor 14, and at armature 189 prepares the circuit for relay C3. In the same manner as just described relay C3 is energized in response to the ninth impulse, and relay C4 is energized in 50 response to the tenth impulse, thereby selecting the desired code ring conductor in accordance with the digit dialled. It will be noticed that the code selecting relay C6 is energized in response to the sixth impulse, and is thereafter maintained 55 in energized position for the remaining impulses in case more than six impulses are transmitted. It will also be noted that the energization of a code selecting relay causes the deenergization of the previously operated code selecting relay, so that the proper code ring conductor is selected in accordance with the digit dialled.

60 When the test circuit was closed in response to the operation of relay C1 the following circuit is closed to the two-step busy relay; from armature 70 75

- 203 of the called line circuit, the multiple connections of the test conductor of called line, armature 223, armature 293, test conductor 117, armature 133 and resting contact, conductor 119, through 5 the upper winding of test relay 300, conductor 138, armature 153, conductor 125, through resistance 325, armature 322, and the winding of two-step marginal busy relay 330 to battery. In case the called line is busy ground will be connected to armature 203 with the result that the busy relay is 10 energized in its first step over the previously traced circuit. Two-step relay 330 operates only its armature 334 to prepare the circuit for fully energizing itself when relay 320 later on de- 15 energizes. Test relay 300 will not energize in the above traced circuit due to the resistance in the winding of busy relay 330 and resistance 325. After the last impulse of the ringing digit slow to release relay 310 deenergizes and opens the circuit to relay 320 which relay thereupon deenergizes. At armature 324 relay 320 opens the circuit of relays 389 and 390, and at armature 322 completes the circuit for operating the busy relay 20 through its second step in case the same is at the 25 time energized in its first step, as follows: from ground at armature 192, conductor 124, armature 334 and working contact, through the normally closed springs controlled by armature 342, through the normally closed springs controlled 30 by armature 322, and through the winding of two-step relay 330 to battery. Relay 330, thereupon energizes in its second step and operates its remaining armatures indicated by the Roman numeral II. At armature 331 relay 330 connects 35 busy tone through the right-hand winding of the repeating coil RC to relay 170 and battery. At armature 332 and resting contact opens a point in the impulsing circuit, at armature 333 grounds conductor 123 for a purpose to be more fully described in making revertive calls, at armature 335 prepares a circuit for the trunk hunting relay 340, and at armature 336 prepares another circuit used in making reverting calls. At this time the 40 busy tone is transmitted from the busy tone source 45 through the busy tone condenser, armatures 341 and 331, conductor 108, through the upper right-hand winding of repeating coil RC and through the winding of relay 170 to battery. Busy tone is thereby induced into the left-hand windings of 50 the repeating coil RC in the well known manner to transmit the tone to the calling subscriber over the heavy talking conductors.
- When the calling subscriber hears the busy tone such subscriber will replace his receiver to cause 55 the release of the apparatus in a manner to be more fully described hereinafter.
- Assuming now that the line called is idle instead of busy, then no circuit is completed for busy relay 330, and therefore the busy relay does 60 not energize in its first step. After the code ringing digit, relays 310 and 320 deenergize as previously described. Relay 320 causes the deenergization of relays 389 and 390, if energized, and at armature 321 completes the circuit for energizing 65 the connector test relay 300 in series with the cut-off relay 201 as follows: from ground by way of armature 192, conductor 124, armature 334 and resting contact, armature 321, conductor 125, through the operated armature on the code selecting relay, such as armatures 153 or 195, conductor 138, through the upper winding of relay 300, conductor 119, resting contact and armature 133, conductor 117, armature 293, armature 223, armature 203 and resting contact, and through 70 the winding of cut-off relay 201 to battery. At 75

armature 206 relay 201 connects ground extending from the link circuit to conductor 233 to mark this line as busy in the calling end of the link, at armature 207 opens the circuit extending to line relay 200, and at armature 208 completes the circuit for energizing slow to release relay 202.

Relay 300, upon energizing, first closes its armature 305 to complete a locking circuit through its lower winding, as well as an energizing circuit for completely operating this relay from grounded 10 lock conductor 14. At armatures 301 and 396, relay 330 connects the talking conductors of the called line to complete the talking circuit, at armature 302 opens a point in the impulsing circuit, at armature 303 connects the pick-up lead extending to the code ringing interrupter to the upper winding of relay 330, and at armature 304 short circuits the upper winding of test relay 300 and likewise connects direct ground to test conductor 117 to maintain this line busy in both the 20 calling and the called ends of the link.

The pick-up and hold conductors shown directly above relay 344 extend to a code ringing interrupter (not shown) wherein the pick-up conductor is grounded at the start of a ringing code cycle 25 while the hold conductor is grounded near the start of the ringing cycle and is maintained grounded until the end of the ringing code cycle is reached. When the pick-up conductor is grounded a circuit may be traced for energizing 30 relay 390 as follows: from ground via pick-up conductor, armature 345, normally closed springs controlled by armature 394, working contact and armature 393 and through the upper winding of relay 392 to battery. At armature 394 relay 390 35 completes a holding circuit for holding itself maintained in operated position during the entire ringing cycle from ground by way of hold conductor, armature 384 and working contact, working contact and armature 393, and through 40 the upper winding of relay 390 to battery. At armature 392 relay 390 connects the selected code ring conductor to the called line.

Assuming now that the code ring digit of the called subscriber is 5 then the fifth code selector 45 relay or relay C5 is energized to connect the code ring conductor 1-3 to the called line. Ringing current from the code ringing interrupter is connected to this conductor to produce one short ring followed by a pause and then three short 50 rings. The ringing circuit extends from the generator at the ringing interrupter over code conductor 1-3, armature 158, resting contact and armature 152, conductor 139, working contact and armature 392, armature 301, conductor 114, armature 292, armature 222, conductor 232, and from thence to the ringers and ground at the stations on this line. Ring back tone is transmitted to the calling subscriber in the following manner: from generator to armature 381, the 60 ring-back tone condenser, conductor 108, through the upper right-hand winding of repeating coil RC to relay 170 and battery, from whence the ring back tone is induced into the left-hand winding of the repeating coil RC in the well known 65 manner to transmit the ring back tone to the calling subscriber.

At the end of the ringing cycle ground is disconnected from the hold conductor in the ringing interrupter with the result that relay 390 now de- 70 energizes to prepare a circuit at armature 392 for the back bridge relay 170. In case the called subscriber has not answered in response to his ringing code the pick-up conductor is again grounded after an interval to again cause the 75

- energization of relay 390. The ringing code is again transmitted to the called line and relay 390 again deenergizes when ground is removed from the hold conductor in the ringing interrupter.
- 5 If the subscriber has answered in the meantime the deenergization of relay 390 now completes a circuit for energizing back bridge relay 170 as follows: from ground at the substation through the left-hand winding of the induction coil, 10 through the receiver and impulse springs, conductor 232 and from thence over the previously traced ringing circuit to armature 301, armature 392 and resting contact, conductor 108, upper right hand winding of repeating coil RC, and 15 through the winding of relay 170 to battery.
- In case the subscribers on this line should have their ringers bridged across the two talking conductors then the generator return circuit would be traced through the substation loop to 20 conductor 231 and thence by way of armatures 221 and 291, conductor 115, armature 306, to ground at armature 347.
- Relay 170, upon energizing over the above traced circuit, at armature 171 opens a point in the circuit used in making reverting calls, at 25 armature 172 and resting contact removes the short circuit from around relay 150 to permit this relay to energize in case the calling line is in non-grounded line, and at the working contact of armature 172 prepares a point in the circuit for energizing the battery reversing relay 120. At armature 172 and working contact relay 170 grounds conductor 129 to complete an energizing 30 circuit for the ring cut-off relay 344 by way of the normally closed springs controlled by armature 345. At armature 345 relay 344 opens a circuit to the upper winding of relay 390 to prevent the reenergization of the latter relay when the pick-up conductor is again grounded, at armature 346 completes a locking circuit for itself from 35 grounded lock conductor 14 as well as opening its original energizing circuit, and at armature 347 disconnects ground from the lower talking conductor.
- 40 In case the calling line is a grounded line similar to line #25, then relay 150 does not energize because it is short circuited from ground on the positive line conductor. This ground will extend over the positive line conductor 1, armatures 11 and 31, conductor 69, armature 106, normally closed springs controlled by armature 122, 45 armature 136 and resting contact, armature 144, through the lower left-hand winding of repeating coil RC, and through the winding of relay 150 to ground. Since relay 150 does not energize, battery reversing relay 120 likewise is not energized to reverse battery to the calling line.
- In case the calling subscriber is on a metallic line like line 15, then relay 150 energizes over the 50 calling subscriber's loop in series with relay 160. At armature 151 relay 150 completes a circuit for energizing the battery reversing relay 120 from ground at the working contact of armature 172. At armatures 121 and 122 relay 120 reverses battery to the calling line for supervisory 55 purposes such as operating a meter or for controlling a pay-station. In this case the talking circuit extends from the ground through relay 150 through the lower left-hand winding of repeating coil RC, armature 144, resting contact and armature 136, armature 121 and working contact, armature 101, conductor 89, armatures 92 and 12, and conductor 2 through the calling 60 substation loop to conductor 1, armatures 11 and 91, conductor 69, armatures 106 and 122, armature 131 and resting contact, armature 141, through the upper left-hand winding of repeating coil RC, and through the winding of line relay 160 to battery. Talking battery to the calling line is furnished through the windings of relays 150 and 160. In case the calling line is a grounded line, such as line 25, the line conductors in the link extending to this line are not reversed and the local battery at the substation 65 circuit provides the talking battery. The talking circuit to the called line extends by way of conductors 231 and 232, armatures 221 and 222, armatures 291 and 292, conductors 114 and 115, armatures 301 and 306, conductors 108 and 109, through the upper and lower right-hand windings of repeating coil RC to battery and ground 70 through the windings of relay 170 and 173. Talking battery on grounded line, such as line 25, is furnished at the substation, while talking battery through the windings of relays 170 and 173 is furnished to metallic lines, such as line 15.
- 75 After conversation and responsive to the called subscriber replacing his receiver, the circuit to back-bridge relay 170 is opened whereupon this relay deenergizes. At armature 172 and its working contact relay 170 opens the circuit of battery reversing relay 120 to cause its deenergization and at the resting contact of this armature short circuits the winding of relay 150 to cause it to deenergize. Battery reversing relay 120, 80 upon deenergizing, reverses battery connections to normal for supervisory purposes. Line relay 160 deenergizes in response to the calling subscriber replacing his receiver and at armature 161 opens the circuit to slow to release relay 180. After an interval slow to release relay 180 deenergizes. At armature 182 relay 180 opens the circuit of slow to release relay 190 and at armature 183 disconnects ground from test conductor 79 to remove the busy ground from the calling 85 line and to open the circuit to the cut-off relay 7 to cause the deenergization of the latter relay. Cut-off relay 7, upon deenergizing, opens the circuit to relay 6 at armature 78, at armatures 77 and 78 reconnects the line relay 8 to ground and 90 the line conductors of line 15 and at armature 76 disconnects the calling test conductor 9 from the called test conductor 3. Relay 6 deenergizes after an interval and restores the line circuit to its normal condition.
- 95 After an interval slow to release relay 190 deenergizes and at armature 192 disconnects ground from conductor 124 to open the locking circuit of relay 313 to cause its deenergization and to open the locking circuit to busy relay 330 in case the same is energized. At armature 193 relay 190 disconnects ground from the connector lock conductor 126 to cause the deenergization of the operated connector unit relay and the operated connector group relay. At armature 194 relay 190 disconnects ground from the lock conductor 14 to cause the deenergization of relay 100, the deenergization of the operated code selecting relay, the deenergization of the operated finder unit relay and the operated finder group relay, 100 and the deenergization of relays 300 and 344. Relay 313, upon deenergizing at armature 314 prepares the dial tone circuit, at armature 315 prepares the circuit for relay 360 and at armature 316 prepares the permanent disconnect circuit. The operated connector unit relay 290 and the operated connector group relay 220 release and disconnect the called line from the link as well as opening the circuit to cut-off relay 201. The deenergization of relay 201 opens 105

- the circuit of slow to release relay 202 which de-energizes after an interval. At armature 207 relay 201 again connects the line relay 200 to line conductor 232.
- 5 Relay 100, upon deenergizing, at armatures 101 and 106 disconnects the talking conductors, and at armature 103 prepares the start circuit for relay 160. The operated code selecting relay C5 deenergizes when ground is removed from lock conductor 14 to restore the code selecting relays to normal. In case the digit 6 or a larger digit has been dialed for the ringing digit, then code selecting relay C6 is likewise deenergized when ground is removed from lock conductor 14. The 10 operated finder unit relay 90 and the operated finder group relay 10 deenergizes and disconnects the line and test conductors of the calling line from the link. Relay 300, upon deenergizing, at armature 394 disconnects ground from the test conductor of the called line and relay 344 deenergizes to restore the link circuits to normal. All of the apparatus and relays are now in their 15 normal position and may be used on subsequent calls.
- 25 *Reverting calls*

A description will now be given of the operations which take place when a subscriber calls another subscriber on his own line. Assuming now that subscriber S desires to make a reverting call and call another subscriber on his own line, and that in response to the removal of the receiver at substation S the first idle link is automatically connected to line circuit #15 in the same manner as previously described. When subscriber S hears the dial tone such subscriber will dial the directory number of the desired called subscriber. In this case, since the desired subscriber is on the same line with subscriber S, the first two digits will be 1 and 5, while the third digit or code ringing digit will be a different digit than subscriber S. In response to the first two digits 1 and 5, the relays in the link circuit operate in the same manner as previously described to connect the calling line to its own line circuit.

45 In response to the code ringing digit the proper code selecting relay is operated to select the code ringing conductor corresponding to the desired subscriber, and the operation of the first code selecting relay completes a circuit for energizing the two-step busy relay in its first step as follows: from ground by way of working contact and armature 183, armature 105, conductor 79, armatures 93 and 13, conductor 9, armature 76, 50 resting contact and armature 86, conductor 3 included in the three-conductor cable 4, armatures 213 and 293, conductor 117, armature 133 and resting contact, conductor 119, through the upper winding of marginal test relay 300, conductor 138, through the operated lower armatures of the code selecting relays, such as armature 153, conductor 125, resistance 325, armature 322, and through the winding of two-step marginal busy relay 330 to battery. Marginal relay 55 300 does not energize over this circuit while the two-step marginal busy relay 330 operates only its armature 334 in its first step. When relays 310 and 320 deenergize after the impulsive period, relay 320 at armature 322 completes the 60 previously traced circuit from grounded conductor 124 for energizing the two-step busy relay 330 in its second step. At armature 331 busy relay 330, upon energizing, in its second step, connects the busy tone to the calling line in the same manner as previously described. At armature

65 333 relay 330 grounds conductor 123 to prepare a circuit for maintaining slow to release relay 190 in operated position and at armature 336 prepares a point in the circuit for the reverting call relay 140.

70 When subscriber S hears the busy tone such subscriber will replace his receiver, thereby opening the circuit through the line relay 160 which thereupon deenergizes. However, since the called subscriber is on the same line as the calling subscriber the operation is somewhat different, and will be described in detail. Line relay 160, upon deenergizing, at armature 161 and its working contact opens the circuit to slow to release relay 180, and at its resting contact completes a circuit for maintaining the cut-off relay 7 in line circuit 15 in energized position as follows: from ground by way of armature 132, armature 161 and resting contact, armature 191, conductor 118, conductor 302, armature 332 and working contact, 15 conductor 119, resting contact and armature 133, conductor 117, armatures 293 and 213, conductor 3 included in cable 4, armature 86 and resting contact, and through the winding of relay 7 to battery. After an interval slow to release relay 25 180 deenergizes. At armature 182 relay 180 opens the circuit of slow to release relay 190, at armature 183 and working contact disconnects ground from conductor 79, and at its resting contact completes the circuit for energizing reverting call 30 relay 140 as follows: from the ground maintaining the cut-off relay 7 energized over conductor 3 as previously described, and thence by way of armature 86 and resting contact, armature 76, conductor 9, armatures 13 and 93, conductor 79, 35 armature 105, armature 183 and resting contact, conductor 128, armature 339, conductor 127, and through the winding of reverting call relay 140 to battery. At armatures 141 and 144 relay 140 opens the circuit extending to the calling line 40 and at armature 142 completes a circuit for maintaining slow to release relay 190 in energized position before the same can deenergize, as follows: from ground by way of armature 333, conductor 123, armature 171, armature 142, and through 45 the winding of relay 190 to battery. At armature 143 relay 140 completes the circuit for operating the connector test relay 300 as follows: from grounded lock conductor 14, armature 143, conductor 137, and through the lower winding of 50 relay 300 to battery. At armature 305 relay 300 completes a locking circuit for itself from grounded lock conductor 14, at armatures 301 and 306 again prepares the ringing circuit, at armature 303 again connects relay 390 to the pick-up conductor, and at armature 304 grounds test conductor 3 by way of armatures 133, 293 and 213 55 for holding the cut-off relay 7 energized and the line busy.

60 From the foregoing it will be seen that in response to the calling subscriber replacing his receiver after receiving a busy signal on making a reverting call that the cut-off relay in his own line circuit is maintained in operated position, that the reverting call relay 140 in the link is operated while the slow to release relay 190 is maintained in operated position, and that the connector test relay 300 is operated to cause ringing current in accordance with the code selecting digit dialled to be transmitted out over his own line to operate the ringers of the substations thereon. When the pick-up conductor in the code ringing interrupter is grounded relay 390 is energized as previously described to connect the selected code ring conductor to the called line. 75

The bells on the called line are then rung in accordance with the code selected.

In response to either the calling subscriber or the called subscriber answering, the following circuit for energizing relay 170 is completed during the silent period when relay 390 is in deenergized position. This circuit may be traced as follows: from ground at armature 347, armature 306, conductor 115, armatures 291 and 211, conductor 1 included in cable 4, through the substation loop to conductor 2, and thence over cable 4 to armature 212, armature 292, conductor 114, armature 301, armature 392 and resting contact, conductor 108, through the upper right-hand winding of repeating coil RC and through the winding of relay 170 to battery. At armature 172 and working contact of relay 170 again completes the circuit for energizing ring cut-off relay 344 to prevent the reapplication of ring-current to the called line, and at armature 171 opens the circuit of slow to release relay 190. After an interval slow to release relay 190 deenergizes and at armature 192 disconnects ground from conductor 124 to open the circuit of relays 313 and 330 to cause their deenergization. At armature 193 relay 190 disconnects ground from the connector lock conductor 126 to open the locking circuits of the operated connector unit relay 290 and the operated connector group relay 210. At armature 194 relay 190 disconnects ground from the lock conductor 14 to open the circuits of relays 100, 344, and 300, the operated finder group relay 10, the operated finder unit relay 90, and the operated code selecting relay. Relay 313, upon deenergizing, prepares the permanent disconnect circuit and the circuit to relay 360. Busy relay 330, upon deenergizing, at armature 336 opens the circuit of relay 140 to cause the latter relay to deenergize. Connector unit relay 290 and connector group relay 210 deenergize and disconnect the line and test conductors of the called line from the link, thereby opening the circuit to back-bridge relay 170 and cut-off relay 7. Finder unit relay 90 and finder group relay 10 deenergize and disconnect the line and test conductors of the line from the link. The operated code selecting relay deenergizes and restores the code selecting relay to normal position. Relay 100, upon deenergizing, opens the talking conductors and prepares the start circuit for line relay 160. Cut-off relay 344, upon deenergizing, again prepares the pick-up circuit. Test relay 300, upon deenergizing, at armature 304 disconnects the ground which has been maintaining the called line busy during this interval. Relays 140 and 170 deenergize to restore the link to its normal condition ready for use in other calls.

When cut-off relay 7 deenergizes, said relay at armatures 78 and 77, completes the circuit for energizing line relay 8 over the subscriber's loop. Relay 8, upon energizing, at armature 86 grounds conductor 3 to maintain this line busy at the called end of the link, and at armature 88 completes the locking circuit for slow to release relay 6 by way of armature 67, so that relay 6 will maintain armature 66 operated to prevent the application of calling battery to test conductor 9. Talking battery to the subscribers on this line is furnished through the windings of line relay 8. After conversation and in response to both subscribers replacing their receivers the circuit through line relay 8 is opened with the result that relay 8 now deenergizes. At armature 88 relay 8 opens the circuit of relay 6 which de-

energizes after an interval to restore the line circuit to its normal position and at armature 86 removes the busy ground.

Trunk calls

5

The local subscribers have access to one group of switch-through trunks. The group of trunks extends to a distant exchange and terminates in the 40-line group in the place of the last three lines in that group. In order for the link to automatically test and hunt for an idle trunk in the group, such trunk lines are provided with two test conductors, and all but the last trunk in the group has these two test conductors strapped together as shown by jumpers 245 and 249 for trunks 43 and 44, respectively. In order for a local subscriber to seize an idle trunk in the group, such subscriber will dial the digits 4 and 3 to connect with the first trunk in the group. In case this trunk is busy, the second trunk, or trunk 44, is tested and should this trunk be busy then the third and last trunk is tested at which point the connection is completed if the trunk is idle and if this trunk should also be busy then the busy tone is transmitted to the calling subscriber.

When a calling subscriber initiates a trunk call the first idle link is connected to the calling line in the same manner as previously described, and in response to the calling subscriber dialling the digits 4 and 3, after receiving dial tone, the connector unit relay 270 and the connector group relay 240 are operated in the same manner as previously described to connect the line and test conductors of the link to the line and test conductors of trunk line 43.

The operation from this point on is slightly different from that previously described and when the connector unit relay 270 is operated the following test circuit is completed to test for the busy condition of trunk 43. In case trunk 43 is busy, then ground will be connected to the test conductor of the trunk line and will extend by way of armature 243, the second upper armature of relay 270, test conductor 117, armature 215 on the operated connector unit relay 270, armature 246 on the operated connector group relay 240, switch-through conductor 116, through the lower winding of marginal switch-through relay 130, armature 181, conductor 125, resistance 325, armature 322, and through the winding of two-step marginal busy relay 330. Switch-through relay 130 does not energize in series with resistance 325 and the windings of relay 330, but the two-step busy relay 330 operates over the above traced circuit to operate only armature 334 to prepare the circuit for energizing the latter relay to its second step. Shortly after the impulsive period following the second digit relays 310 and 320 deenergize and relay 320 at armature 322 completes the circuit from grounded conductor 124 for operating busy relay 330 in its second step. At armature 335 busy relay 330 completes the circuit for energizing trunk hunting relay 340 as follows: from ground on the busy test conductor of the called trunk line, armature 243, and thence by way of jumper 245 to armature 244, through the upper armature of relay 270, conductor 319, armature 312, armature 335, and through the winding of relay 340 to battery. At armature 341 relay 340 disconnects the busy tone from the upper talking conductor, at armature 342 opens the locking circuit of two-step busy relay 330, as well as preparing a new test circuit for maintaining busy relay 330 in energized position in case the 75

- next or second trunk 44 is busy, and at armature 343 connects ground to the trunk hunting conductor 299 to complete the circuit for energizing connector unit relay 289 as follows: from ground connected to the extra test conductor 319 by means of the ground extending from the trunk test conductor over jumper 245 as previously traced, armatures 312 and 335, armature 343, conductor 299, armature 298, armature 288 and resting contact, armature 278 and working contact, and through the winding of connector unit relay 280 to battery. The release time of the connector unit relays are less than the energizing time, and relay 289, upon energizing, closes first its locking circuit at armature 287 and then operates its armature 286 to open the locking circuit of connector unit relay 270 to cause the latter relay to deenergize. At its upper armatures connector unit relay 280 connects the line and test conductors of the second trunk 44 to the link, at armature 285 maintains the switch-through circuit, at armature 283 and resting contact opens the original energizing circuit of relay 280, and at its working contact prepares and closes the circuit for relay 280 which is slightly slow to operate. Relay 270, upon deenergizing, at its upper armatures disconnects the line and test conductors of the first trunk line or trunk 43 from the link. After connector unit relay 270 deenergizes and before connector unit relay 299 has had sufficient time to fully energize the following test circuit is completed to determine if the second trunk or trunk 44 is busy or idle. If idle, busy relay 330 immediately falls back to open the circuit grounding the trunk hunting conductor 299 to prevent the energization of connector unit relay 290. If case the second trunk is busy, then busy relay 330 is maintained in energized position over the following circuit: from ground on the test conductor of the second trunk line, through the test armatures on the operated connector group relay 249 and the operated connector unit relay 289 to conductor 117 and thence by way of armature 133 and resting contact, conductor 119, armature 342 and working contact, the normally closed springs controlled by armature 322, and through the winding of two-step busy relay 330 to battery. The busy ground on the test conductor of the second trunk line also extends through the jumper 249 through the extra test armatures on relays 249 and 280, extra test conductor 319 and thence by way of armatures 312 and 335 for maintaining relay 340 in operated position. This same ground extended by way of armature 343 and trunk hunting conductor 299, armature 298, and armature 288 and working contact through the winding of connector unit relay 299 for energizing the latter relay. At armature 297 relay 290 first completes its own locking circuit to ground lock conductor 126, at armature 296 opens the locking circuit of connector unit relay 289 to cause the latter relay to deenergize, at armature 298 opens its original energizing circuit, at armature 295 maintains the switch-through circuit, and at armature 291 to 294, inclusive, connects the line and test conductors of the third or last trunk line 45 to the link. Connector unit relay 289, upon deenergizing, at its upper armatures disconnects the line and test conductors of the second trunk line from the link. As previously described, the last trunk line in the trunk group does not have its two test conductors connected together with a jumper such as the preceding trunks with the result that no further trunk hunting takes place, regardless of whether the trunk
- is idle or busy. In case the last trunk line is busy, then busy relay 330 is maintained energized but in this case since no connection is completed for the extra test conductor 319 the circuit to relay 340 is opened with the result that this relay now deenergizes. At armature 341 relay 340 connects busy tone to the upper talking conductor to cause the transmission of busy tone to the calling line, as previously described, and at the normally closed springs controlled by armature 342 completes the previously traced locking circuit for busy relay 330. When the calling subscriber hears the busy tone such subscriber will replace his receiver and release the link circuit in the same manner as previously described.
- As soon as an idle trunk is connected to the link the circuit for busy relay 330 is no longer completed with the result that this relay now deenergizes if energized, whereupon a circuit is completed for energizing the switch-through relay 130 as follows: from ground by way of armature 192, conductor 124, armature 334 and resting contact, armature 321, conductor 125, armature 181, through the lower winding of switch-through relay 130, conductor 116, to armature 246 and through the operated switch-through armatures on the connector unit relay, such as armatures 295, 285 or 275, conductor 117, through the operated test armature on the operated connector unit relay, through the test armature on the operated connector group relay, such as armature 243, and thence by way of the test conductor of the idle trunk to battery thereon. At armatures 131 and 136 switch-through relay 130 switches the talking conductors and opens the circuit to line 35 relay 180. At armature 132 opens the impulsive circuit and the circuit to relay 180, at armature 133 opens the original test circuit and closes the circuit for holding slow to release relay 190 energized from ground fed back from the trunk over the trunk test conductor, at armature 134 locks itself through its upper winding from ground fed back over the trunk, and at armature 135 grounds conductor 79 by way of armature 105 to maintain the calling line busy and the cut-off relay 7 energized after the slow to release relay 180 deenergizes.
- When relay 130 at armatures 131 and 136 switches the talking conductors straight through to the called trunk, a circuit is completed in the trunk circuit for causing ground to be connected to the test conductor of the trunk line as follows: this circuit may be traced as follows: through the calling subscriber's loop, conductors 1 and 2, armatures 11 and 12, 91 and 92, conductors 19 and 28, armatures 191 and 196, normally closed springs controlled by armatures 121 and 122, armatures 131 and 136 and their working contacts, conductors 114 and 115, through the operated line armatures on the operated connector unit and connector group relays over the negative and positive line conductors of the trunk line to ground and battery through the winding of a relay in the trunk line. The operation of this relay in the trunk line circuit causes ground to be connected to the test conductor of the trunk for maintaining slow to release relay 190 in operated position. This circuit may be traced from ground on the trunk test conductor through the operated test armatures of the operated connector unit and connector group relays, test conductor 117, armature 133 and working contact, and through the winding of relay 190 to battery. Marginal switch-through relay 130 is maintained energized over its upper winding from grounded test conductor 75.

117, by way of armatures, such as armatures 295, 285, or 275, on the operated connector unit relay, armature 246, switch-through conductor 116, armature 134 and through the upper winding of switch-through relay 130 to battery.

Line relay 160 and later on relay 180 deenergize. At armature 181 relay 180 opens the original energizing circuit of switch-through relay 130 and at armature 182 opens the original energizing circuit of slow to release relay 190 which is now held energized from ground sent back over the test conductor of the trunk line. The subscriber's line is now connected direct to the line conductors of the trunk line and the subscriber now dials the number of the desired main exchange subscriber's line in case the trunk terminates in an automatic exchange, or the operator completes the connection to the main exchange subscriber in the well-known manner in case the trunk terminates in a manual exchange. Talking battery to the local subscriber is furnished from the main exchange over the trunk line.

The release of the local link circuit is controlled from the main exchange, and in response to the main exchange subscriber replacing his receiver or the operator disconnecting, ground is removed from the test conductor of the called trunk line to cause the deenergization of relays 130 and 190. Relay 130, upon deenergizing when ground is removed from the test conductor of the trunk line, at armature 135 disconnects ground from conductor 79 to open the circuit of cut-off relay 7 to cause the latter relay to deenergize. Slow to release relay 190, after an interval deenergizes and causes the deenergization of the operated finder unit and finder group relays, the deenergization of the operated connector unit and connector group relays and the deenergization of relay 313, thereby restoring the link circuit to its normal condition for use in other calls.

When an incoming trunk call is made on one of the trunk lines the line relay in the trunk line grounds the start conductor, similar to start conductor 5 or 5' for this line group, to cause the operation of the finder unit and group relays as previously described, to connect the calling end of the link to the trunk line. The main exchange subscriber after hearing the dial tone then dials the local subscriber's number and the connection is completed in the same manner as previously described.

Permanent lines

Permanent lines are lines which are shorted or grounded due to some fault and in some cases of trouble they cause the line relays, such as line relay 8, to operate and initiate a call the same as when a subscriber initiates a call. In case of trouble of this nature the finder unit relay and the finder group relay operate as before to connect the line to an idle link. This link is held by the permanent line. When all the links become busy ground is disconnected from the all link busy conductor ALB in Fig. 3 by the operation of all the relays 190 in all of the links. A predetermined time after ground is disconnected from the all link busy conductor ALB the permanent disconnect lead Perm. Disc. is grounded. Since no dialling has taken place relay 313 is not energized and when the permanent disconnect lead is grounded relay 140 is energized in the following circuit: from grounded permanent disconnect lead Perm. Disc. armature 316, conductor 127, and relay 140 to battery. At armatures 141 and 144 relay 140 opens the talking con-

ductors extending to the line with the result that line relay 160 now deenergizes. Shortly thereafter relay 180 deenergizes to open the circuit of relay 190 at armature 182, and at armature 183 opens the circuit of the cut-off relay in the line circuit. After an interval slow to release relay 190 deenergizes to accomplish the same functions as previously described, and at armature 194 and its resting contact grounds the all link busy conductor ALB to cause ground to be disconnected from the permanent disconnect conductor Perm. Disc. When ground is disconnected from the permanent disconnect conductor relay 140 deenergizes and this link circuit is now available for use with other lines. When the cut-off relay, 15 such as relay 7, deenergizes in response to the operation of relay 140, cut-off relay 7 reconnects the line relay, such as 8, across the line conductors to cause the line relay to again energize. Since relay 6 is a slow to release relay the 20 energization of relay 8 at armature 88 completes the locking circuit for relay 6 by way of armature 67 before the relay 6 can de-energize. At armature 86 line relay 8 maintains this line busy to prevent connection thereto, while the operation 25 of relay 6 maintains the start circuit 5 open. Relays 8 and 6 are maintained until the trouble is cleared.

The invention having been described, what is considered to be new is pointed out in the appended claims.

What is claimed is:

1. In a telephone system, groups of lines, a plurality of links for interconnecting said lines, a first and a second relay group in each of said links, means responsive to a line in one of said groups initiating a call for marking such group as calling and for seizing an idle one of said links, means responsive thereto for operating the relay corresponding to the calling group in the first relay link group, means operated by said relay for marking the calling line in the second relay link group, and means for thereafter sequentially operating the relays in the second link group to test for and find the marked calling line. 35

2. In a telephone system, a group of lines, each line having a test conductor, a link for interconnecting said lines, a relay in said link corresponding to said group of lines, a group of relays in said link, means responsive to a line in said group initiating a call for marking its individual test conductor with calling potential and for operating said link relay to connect all the test conductors of said group of lines to said group of relays, means for thereafter sequentially operating the relays in said group in search of the test conductor having calling potential thereon, and means operated when the calling potential is found for stopping further sequential operation of said relays. 50

3. In a telephone system, groups of lines, a group of relays common to said lines, means responsive to the initiation of a call on a line in one of said groups for marking that group with calling potential in the relay group, means operated responsive thereto for sequentially operating said relays in search of said calling potential, and means operated when said calling potential is found for stopping further sequential operation of said relays. 65

4. In a telephone system, a group of lines comprising both subscribers' lines and trunk lines, a link for interconnecting said lines, a group of relays in said link, each of said relays correspond- 75

- ing to a line in said group, testing means in said link, and means responsive to a calling subscriber dialling the number designating a trunk call in this group of lines for sequentially operating the 5 relays corresponding to the trunk lines in this group of lines to successively connect the trunk lines to said testing means until an idle trunk line in the group is found.
5. In a telephone system, a group of lines comprising both subscribers' lines and trunk lines, a link for interconnecting said lines, a group of relays in said link, each of said relays corresponding to a line in said group, testing means in said link, a circuit controlled by each of said relays 10 when operated for connecting the line corresponding to such operated relay to said testing means, means for operating said relays to connect the subscribers' lines in said group over said 15 circuits to said testing means in response to a calling subscriber dialling the numbers designating the calls to subscribers' lines in said group, and means for sequentially operating the relays corresponding to said trunk lines to successively 20 connect the trunk lines of said group to said testing means until an idle trunk line is found in case the calling subscriber dials the number designating a trunk call in this group.
6. In a telephone system, groups of lines, one of said groups comprising both subscribers' lines 25 and trunk lines and some of said groups comprising only subscribers' lines, a link for interconnecting said lines, a group of relays in said link, each said relay corresponding to a line in each of said groups of lines, testing means in said link, means responsive to a calling subscriber dialling the group digit of a called subscriber's number 30 for connecting the group of lines corresponding to said digit to said relay group, means responsive to the calling subscriber dialling the units digit 35 for operating the relay in said group corresponding to the called line in this group, circuits completed by the operation of each relay of said group for connecting only the line of the connected group corresponding to such operated relay to said testing means, and means responsive to a calling subscriber dialling the number designating a trunk call in said one group of lines for 40 connecting such group of lines to said relay group and for sequentially operating the relays in said 45 group corresponding to successive trunk lines in this group to successively connect such trunk lines to said testing means until an idle one of said trunk lines in the group is found.
7. In a telephone system, a calling line, a called 50 party line, means responsive to a subscriber on the calling line initiating a call and dialling a plurality of digits of a called subscriber's number on said called line for extending a connection to the called line, code selecting relays operated responsive to the calling subscriber dialling the 55 last digit of the called subscriber's number for signalling the called subscriber on the called line in case the called line is idle, a testing circuit over which the called line is tested for its busy or idle condition, and contacts operated on the 60 first code selecting relay in response to the first impulse of the last digit for completing said testing circuit.
8. In an impulse repeating arrangement, a line 65 relay and a line over which it is energized, a pulse relay, a third relay controlled by said pulse relay, a circuit for said pulse relay jointly controlled by said line relay and said third relay, and means including said pulse relay for energizing said third relay in response to each alternate energi- 70 zation of said line relay and for deenergizing said third relay in response to the other alternate energizations of said line relay when a series of impulses is transmitted to said line relay over said line.
9. In a telephone system, subscribers' lines and trunk lines, an all relay finder-connector link, relays in said link, means responsive to calls for operating said relays to complete local connections between subscribers' lines and trunk connections 75 between trunk lines and subscribers' lines, a source of talking battery in said link, a source of talking battery in each trunk line, means for feeding talking battery from said link to the calling and called subscribers' lines in local connections, and means for disconnecting said link source and for feeding talking battery from the trunk line source to a subscriber connected in a trunk connection.
10. In a telephone system, groups of lines, a plurality of links for interconnecting said lines, 80 a group of relays in each link, each relay in each group corresponding to a group of lines and corresponding relays in different relay groups corresponding to the same group of lines, contacts on each of said relays, and means responsive to the initiation of a call on one of said lines for connecting calling potential to the contacts of the relay in each link corresponding to the group the calling line is in to mark only the calling group in each link.
11. In a telephone system, groups of lines, a plurality of links for interconnecting said lines, a group of relays in each link, each relay in each group corresponding to a group of lines, contacts on each of said relays, means responsive to the initiation of a call on one of said lines for connecting calling potential to the contacts of the relay in each link corresponding to the group the calling line is in to mark the calling group in each link, a group test relay in each link, means 85 also responsive to the initiation of said call for seizing an idle one of said links and for sequentially operating the group relays in the seized link to find said calling potential and connect such calling potential through the operated contacts of the corresponding group relay to the group test relay in said link, and a circuit completed responsive thereto for energizing said group test relay to prevent further sequential operation of said group relays.
12. In a telephone system, groups of lines, a plurality of links for interconnecting said lines, a first and a second group of relays in each link, each relay in each first group corresponding to a group of lines and corresponding relays in different first groups corresponding to the same group of lines, each relay in each second group corresponding to a line in each of said group of lines and corresponding relays in different second groups corresponding to the same line, means 90 responsive to the initiation of a call on one of said lines for seizing an idle one of said links, for then sequentially operating the relays in the first group of said link to test for and find the group the calling line is in, and for thereafter sequentially operating the relays in the second group of said link to test for and find the calling line in the calling group.
13. In a telephone system, groups of lines, a plurality of links common to said lines, a first and 95 a second group of relays in each link, there being a first group relay in each link for each group of lines and each such relay having contacts for connecting all the lines of its corresponding group to the associated second group relays in the same 100

- link, there being as many second group relays in each link as there are lines in any one group and each such relay having contacts for connecting a given line in any group dependent upon which one of the associated first group relays is operated, means responsive to the initiation of a call on one of said lines for connecting group calling potential to the group relays in each link and for marking the calling line with line calling potential, means also responsive to the initiation of a call for seizing an idle one of said links, means responsive to said seizure for sequentially operating the first group relays in the seized link to find the group calling potential, means responsive to said first group relays finding said group calling potential for stopping further sequential operation of said first group relays and for connecting said line calling potential to the second group relays in said link, and means responsive thereto for sequentially operating the second group relays in the seized link until said line calling potential is found to operatively connect the calling line to said link.
14. In an impulsing system, an impulsing relay, an impulse repeating relay, means for de-energizing said impulsing relay a plurality of times to transmit impulses, means for energizing said repeating relay in response to each odd impulse transmitted by said impulsing relay and for deenergizing said repeating relay in response to each even impulse transmitted by said impulsing relay, selecting means, an odd and an even pulse conductor extending to said selecting means, and contacts on said repeating relay for grounding the odd pulse conductor on each energization of said repeating relay and for grounding the even pulse conductor on each deenergization of said repeating relay to operate said selecting means to make a selection.
15. In an impulsing system, an impulse repeating relay, an odd and an even pulse conductor, means for energizing and deenergizing said impulse repeating relay a plurality of times, a group of selecting relays, means for energizing the first selecting relay in response to the first energization of said impulse repeating relay, means for energizing the second selecting relay over said even pulse conductor in response to the first deenergization of said impulse repeating relay, means for energizing the third selecting relay over said odd pulse conductor in response to the second energization of said impulse repeating relay, means for energizing the remaining selecting relays over said even and odd pulse conductors in the manner set forth in response to subsequent deenergizations and energizations of said impulse repeating relay, and a locking circuit for each selecting relay except the last controlled by the succeeding selecting relay.
16. In an impulsing system, an impulse repeating relay, an odd and an even pulse conductor, means for energizing and deenergizing said impulse repeating relay a plurality of times, a group of selecting relays, means for energizing the first selecting relay in response to the first energization of said impulse repeating relay, means for energizing the second selecting relay over said even pulse conductor in response to the first deenergization of said impulse repeating relays, means for energizing the third selecting relay over said odd pulse conductor in response to the second energization of said impulse repeating relay, means for energizing the remaining selecting relays over said even and odd pulse conductors in the manner set forth in response to the first deenergization of said impulse repeating relay, a locking circuit for each selecting relay upon energizing for opening the locking circuit of the preceding selecting relay to cause its deenergization, and means for preventing the reenergization of any preceding selecting relays in response to the energizations and deenergizations of said impulse repeating relay.
17. In a selecting system, an impulse repeating relay, an odd pulse conductor and an even pulse conductor, means for energizing and de-energizing said repeating relay a plurality of times, a lock conductor, a group of selecting relays, means for connecting said lock conductor to the first selecting relay for energizing the same in response to the first energization of said repeating relay, means controlled by said first selecting relay for completing a locking circuit for itself including said lock conductor and for connecting the second selecting relay to said even pulse conductor, said second selecting relay energized over said even pulse conductor in response to the first deenergization of said repeating relay, means controlled by said second selecting relay for completing a locking circuit for itself including said lock conductor, for opening the locking circuit of the first selecting relay to cause its deenergization, and for connecting the third selecting relay to said odd pulse conductor, said third selecting relay energized over said odd pulse conductor in response to the second energization of said repeating relay, means controlled by said third selecting relay for completing a locking circuit for itself including said lock conductor, for opening the locking circuit of the second selecting relay to cause its deenergization, and for connecting the fourth selecting relay to said even conductor, and the remaining selecting relays energizing over connections to the even and odd pulse conductors prepared by the preceding relay, locking over the lock conductor, and deenergizing when the succeeding relay is energized in the manner set forth in response to subsequent deenergizations and energizations of said repeating relay to make a selection.
18. In a telephone system, a link circuit, a group of trunk lines accessible to said link circuit, a first and a second test conductor for each trunk line, connecting means permanently connecting the first test conductor with the second test conductor on each trunk line except the last in said group, means for energizing the relay corresponding to the first trunk line in the group to connect such trunk line to said link circuit, a circuit including the first and second test conductors and the associated connecting means of the first trunk line for energizing the relay corresponding to the second trunk line in case the first trunk line is busy to connect the second trunk line to said link circuit, and means controlled by the energization of the second trunk relay for deenergizing said first trunk relay to disconnect the first trunk line from said link circuit.
19. In a telephone system, a group of lines comprising both subscribers' lines and trunk lines, a link for interconnecting said lines, a group of relays in said link circuit, each of said relays corresponding to a line in said group, testing means in said link, means responsive to a calling subscriber dialling the group digit of a called subscriber's line in said group for connecting said

- group of lines to said relay group, means responsive to said subscriber dialling the unit digit for operating the relay corresponding to the called line, circuits completed by the operation of each 5
5 said relay for connecting only the line corresponding to such operated relay to said testing means, and means responsive to the calling subscriber dialling the number designating a trunk call in this group of lines for operating said first 10
10 means to connect this group of lines to said relay group for operating said second means to connect the first trunk in the group, and for thereafter sequentially operating the remaining relays in said group corresponding to the successive 15
15 trunk lines to successively connect such trunk lines to said testing means until an idle one of said trunk lines is found.

20. In a telephone system, a group of lines comprising subscribers' lines and trunk lines, each

line having a test conductor, a link for interconnecting said lines, a relay in said link corresponding to said group of lines, a group of relays in said link, each of said group relays corresponding to a line in said group, means responsive to a calling subscriber dialling the number designating a trunk call in this group of lines for operating said relay to connect the test conductors of all said lines to said group of relays, testing means in said link, and means also responsive to the calling subscriber dialling the number designating a trunk call for sequentially operating the relays in said relay group corresponding to the trunk lines in this group of lines to successively connect the test conductors of successive trunk lines to said testing means until an idle trunk line in the group is found. 10 15
